AIR-COOLING OF GLASS BULB RECTIFIERS

Franz Geyer, Vienna, Austria, assignor to "Elin"
Aktiengesellschaft für elektrische Industrie,
Vienna, Austria

Application May 14, 1930, Serial No. 452,496
In Austria August 28, 1929

13 Claims. (Cl. 250—27.5)

This invention relates to a new and improved cooling system for the containers of glass bulb rectifiers. In the arrangement generally followed the fan producing the cooling current of air is situated below the bulb and blows a stream of air upwards on to the cathode, past the arms, and finally towards the cooling head. This arrangement is dictated by the consideration, strictly correct from a physical point of view, that the resistance to the movement of the cooling air is slightest and the heated air can be most rapidly disposed of without danger of its returning to the container to be cooled if the stream of cooling air is directed upwards, following the natural tendency of heated air to rise. The anode arms, however, impede the even flow of the air and give rise to the formation of eddies, so that cylindrical or conical guide sheets are frequently employed in the attempt to obtain adequate draught over the surface of the cooling head. If the distribution of the temperature of a glass bulb cooled in the manner indicated is examined it will be found that precisely that portion which should be maintained coolest, namely the cooling head, is swept by a current of air which has become heated by contact with the hottest parts of the bulb, the anode arms. But even if the quantity of the cooling air employed be increased to such an extent that the air in traversing the region of the bulb does not become appreciably heated, this arrangement nevertheless has the further drawback that the crown of the cooling head remains out of reach of the cooling current and is rendered valueless for cooling purposes.

In accordance with the present invention the above-mentioned drawbacks are avoided by the provision of a cooling system in which the current of cooling air is blown downwards from above on to the glass container, so that the fresh air current is caused to meet first the coolest portion of the bulb namely the cooling head. The warmed air driven downwards has naturally the tendency to rise again by the shortest route and to mix with the fresh cooling air, which would result in a very considerable reduction of the cooling effect. This tendency can be counteracted by the suitable erection of the rectifying cell or by the suitable shaping of the chamber or space in which the same is mounted. Even then, however, the flow of the cooling current is apt to be irregular in consequence of the presence of the anode arms. An improvement in this latter respect can be obtained by the inclu-

sion of various auxiliary means, as shown in the accompanying drawings, in which:—

Fig. 1 shows in elevation a rectifier with a guide sheet surrounding the cooling head.

Fig. 2 is a similar elevation of a modified form of construction embodying subsidiary deflecting sheets.

Fig. 3 shows in elevation a rectifier with a cylindrical cooling head and appropriate air guiding sheets.

Figs. 4 to 6 illustrate specially formed guiding and deflecting sheets for use in connection with bulbs having cylindrical cooling heads with re-entrant cooling surfaces.

Figs. 7 and 8 illustrate modifications embodying a by-pass for a portion of the cooling air current.

Referring to Fig. 1 an air guiding sheet 4 is interposed between the cooling head 1 and the anode arms 2, so that a current of air generated for instance by a fan *v* and directed downwards from above is divided into two parallel streams, of which the inner stream is capable of carrying the greater quantity of air and plays over the whole length of the main body of the bulb 1 together with the inner portion of the lower arms 2' and the cathode 3, while the outer stream sweeps past the anode arms 2 and the remaining portion of the lower arms 2'.

Since however experience has shown that an intensive cooling of the anode arms 2 is not always desirable it has proved preferable, under certain circumstances, to provide the arrangement of guide sheets shown in Fig. 2. In this form of construction the current of air is deflected below the cathode by means of a second sheet 5, which diverts the stream of air either partially or entirely along the anode arms in an upward direction, so that the anode arms 2 are only swept by preheated air and are protected from becoming cooled to too great an extent. The required draught of air can either be generated by a fan *v* situated immediately above the bulb, as indicated in Figs. 1 and 2, or can be generated by a fan or blast mounted independently of the rectifier, conducted to the latter by means of a pipe line, and finally caused to impinge on the bulb from above.

It has proved advisable in the case of high capacity glass bulb rectifiers to depart from the hitherto usual pear shape of bulb, and to adopt a slender shape, which could be strictly cylindrical except for considerations of strength, for the cooling head. This form makes possible the provision of exact air guidance with comparatively slight current cross-section, which leads neces-

sarily to an increase in the rate of flow of the cooling air, and at the same time to a considerable intensification of the cooling effect.

Fig. 3 shows diagrammatically an arrangement of this type, wherein 1' denotes the glass bulb, 4' the guiding sheet disposed parallel to the cooling space proper, and 5' the sheet which deflects the current of air partly to serve for the cooling of the arms 2, and partly for cooling the lower part of the bulb below the cathode 3.

In some rectifiers the cooling head is provided with a reentrant portion to increase its cooling effect. The system of guide sheets required for cooling such a bulb in accordance with my invention is shown diagrammatically in Fig. 4, in which the guide sheets are represented by 4', 5', and 6'; the course taken by the cooling air being clearly indicated by the arrows. Here again the counter-current principle (the cooling air travelling in the opposite direction to the mercury vapour) is rigidly adhered to for the cooling of the cooling space proper.

The exact air guidance typified by confined air spaces surrounding the cooling chambers proper is common to the last-mentioned type of bulb, and requires, as already mentioned, high rates of flow of the cooling air in order that adequate quantities thereof can be forced through the narrow air channel cross-sections. It is not always possible to develop the pressure required for this purpose by means of fans, so that it is frequently necessary to employ blowers with pressures up to 200 mm. (about 8 ins.) water column for the generation of the air current. It is however by no means necessary to provide a blower dimensioned for the same quantity of air as would be required if the draught were generated by means of a fan. The cooling effect of the air is far more favourable with high rates of flow, and under these conditions the cooling air is almost perfectly exploited, that is to say leaves the region of the bulb at a uniform temperature, while the air blown past the bulbs by fans is very irregularly heated; so that only a small proportion thereof can be regarded as effective for cooling purposes.

This exact air guidance by means of closed guiding sheets with the more favourable effect obtainable by means of a regulated current at a high rate of flow can only be realized with simple means in the case of the bulbs of a slender shape, and then only along the actual cooling chamber 1', while slower rates of flow and more or less unregulated currents occur in the case of complicatedly shaped arms 2, insofar as the latter are not individually cased in. But since a too extensive casing in of the glass container is preferably avoided in view of difficulties in erecting and dismantling it can become necessary to increase the amount of the cooling air delivered by the blower beyond that which is necessary for the cooling head proper in order to obtain an adequate current along the arms 2 and the lower portion 3 of the bulb. The delivery of large quantities of air at high pressure has, however, a detrimental effect on the efficiency of the plant, on account of the considerable consumption of power required therefor. It is thus more advisable to conduct to the cooling head 1' only the actual quantity of air required, and to use the speed of this primary air current at the exit from the annular space 4'' (Fig. 5) in conjunction with a further sleeve 7 to obtain an injector-like effect capable of setting up a subsidiary current adequate for the suitable cooling of the arms and of the lower portion of the bulb. By this means the

consumption of energy can be kept down to a minimum. Air under pressure is supplied to the upper end of casing 4' by blower 15.

The arrangement as shown in Fig. 5 complies with the various requirements enumerated and takes account of the temperatures in the cooling chamber 1' and at the anode arms 2, providing for the former a smaller quantity of air with a vigorous blowing effect at a high rate of flow, and for the latter a larger quantity of air at a lower rate of flow. A similar result can be achieved by the combined use of a blower and of a fan v_1 . This arrangement is shown in Fig. 6. The cooling head proper 1' is again equipped with the guide sheets 4' and 6' and is played upon from above by the draft from the blower 15. At 4'' the blower draft mixes with the stream of air generated from below by the fan v_1 , for which latter stream a guiding sheet 5' is likewise provided, which ensures the proper cooling of both the cathode portion 3 of the bulb and the anode arms 2.

The effect achieved by the use of an auxiliary fan can also be achieved by an arrangement as shown in Fig. 7, in which a portion of the air blown against the cooling head is diverted by means of a branch pipe 8, conducted through a by-pass 9 and blown through an opening 10 against the cathode portion of the bulb. This arrangement has the advantage of being considerably simpler in construction than that employing a separate fan for the cathode portion (v₁ in Fig. 6).

Fig. 8 illustrates the employment of the above-described principle in connection with a rectifier bulb having a re-entrant cooling extension 6 with the air guiding tube 6' pertaining thereto in an arrangement in which the downwardly directed air current is divided into three portions of which the one is blown directly on to 40 and past the cooling head, while the second is directed by means of the tube 9 against the cathode, and the third is directed into the cooling extension 6 whence this portion of the air current is discharged into the outer air through 45 the bent tube 6'. This arrangement develops a particularly advantageous cooling effect.

I claim:—

1. In combination with a glass bulb rectifier having a cooling head, anode arms, and a cathode, means for generating a current of air, and means for directing said current of air against the top of said cooling head and causing said current to flow along the entire outer surface of said cooling head and across said anode arms in the direction of said cathode.

2. In combination with a glass bulb rectifier having a cooling head, anode arms extending laterally with respect to said cooling head, and a cathode, means for generating a current of cooling air, and means for directing said current against the top of said cooling head and causing said current to flow along the entire outer surface of said cooling head and across said anode arms in the direction of said cathode, said means comprising guide surfaces surrounding said cooling head and located between the latter and said anode arms.

3. In combination with a glass bulb rectifier having a cooling head, anode arms extending laterally with respect to said cooling head, and a cathode, a guide sheet surrounding said cooling head in spaced relation thereto between the latter and said anode arms, a guide sheet located below said anode arms, and means for

generating a current of air and directing the same against the upper end of said cooling head, said first mentioned guide sheet being adapted to guide the current of air along said cooling head, and said second mentioned guide sheet being adapted to deflect the current of air outwardly along said anode arms.

4. In combination with a glass bulb rectifier having anodes, a cathode, and a substantially cylindrical cooling head, substantially cylindrical guide means surrounding said cooling head and forming a narrow passage around the same, and means for maintaining a supply of air under pressure in the end of said guide means further from said cathode.

5. In combination with a glass bulb rectifier having a substantially cylindrical cooling head, anode arms extending laterally with respect to said cooling head, and a cathode, a substantially cylindrical guide sheet surrounding said cooling head in spaced relation thereto and forming a narrow passage around the same, a guide sheet below said anode arms, and means for maintaining a supply of air under pressure in the end of said first mentioned guide sheet furthest from said cathode, said second mentioned guide sheet being adapted to deflect air issuing from the adjacent end of said first mentioned guide sheet outwardly along said anode arms.

6. The combination with a device as specified in claim 4, of a sleeve surrounding the end of said guide means nearest said cathode and spaced therefrom in such relation as to produce an injector effect on the air in the vicinity of the bulb.

7. The combination with a device as specified in claim 4, of a sleeve surrounding the end of said guide means nearest said cathode and spaced therefrom in such relation as to produce an injector effect on the air in the vicinity of the bulb, and a guide sheet below said anode arms adapted to deflect the air outwardly along said arms.

8. In combination with a glass bulb rectifier having a cooling head, anode arms extending laterally with respect to said cooling head, and a cathode, a guide sheet surrounding said cooling head in spaced relation thereto and between the latter and said anode arms, means for generating a current of air and directing the same against the top of said cooling head, whereby said current is caused to flow along said cooling head in the direction of said cathode, and an

auxiliary fan adapted to generate an additional stream of cooling air impinging against said cathode and flowing toward said anode arms.

9. In combination with a glass bulb rectifier having anodes, a cathode, and a substantially cylindrical cooling head, substantially cylindrical guide means surrounding said cooling head and forming a narrow passage around the same, means for maintaining a supply of air under pressure in the end of said guide means furthest from said cathode, and an auxiliary fan adapted to blow additional cooling air against the cathode of said rectifier and toward said anode arms.

10. In combination with a glass bulb rectifier having a cooling head, anode arms extending laterally with respect to said cooling head, and a cathode, a guide sheet surrounding said cooling head in spaced relation thereto and between the latter and said anode arms, means for generating a current of air within said guide sheet directed against the upper end of said cooling head and flowing along said cooling head toward said cathode, and means for by-passing a portion of said air current from above said cooling head and directing the same against said cathode in a direction opposed to the main current of air.

11. In combination with a glass bulb rectifier having a cathode, anodes, and a cooling head provided with a re-entrant cooling surface, guide means surrounding said cooling head, means for blowing a current of air within said guide means toward the re-entrant portion of said cooling head, and a tube leading from the exterior of said guide means into said re-entrant portion and terminating near the inner end thereof.

12. In combination with a glass bulb rectifier having a cathode, anodes, and a cooling head provided with a re-entrant cooling surface, means forming a casing surrounding said cooling head in spaced relation thereto, means for supplying air under pressure to the end of said casing remote from said cathode, and a tube leading from the exterior of said casing into said re-entrant cooling portion and terminating near the inner end thereof.

13. A device as described in claim 11 in which said tube is centrally located within said re-entrant portion and of such diameter as to form a relatively narrow passage between the same and said re-entrant portion.

FRANZ GEYER.
